A. F. Toulmir

UNITED STATES PATENT OFFICE.

ALFRED F. TOULMIR, OF ELLICOTT'S MILLS, MARYLAND.

RAILROAD-CAR BRAKE.

Specification of Letters Patent No. 26,307, dated November 29, 1859.

To all whom it may concern:

Be it known that I, ALFRED F. TOULMIR, of Ellicott's Mills, in the county of Howard, in the State of Maryland, have invented a new and Improved Car-Brake; and I do hereby declare that the following is a full and exact description thereof, reference being had to the accompanying drawings, whereof—

10 Drawing No. 1 is a view of the bottom of the car (as seen from the track) with the car in motion, and the cams free of the brake-blocks, or in other words the brakes up. Drawing No. 2 is a view of the bottom 15 of the car (as seen from the track) with the car coming to, or at, a rest, (with cams pressing against the brake blocks) or in other words the brakes down. Drawing No. 20 3 represents the elevation of either end of the car, showing the connection between the engineer's, brakeman's, or conductor's brake-cord and the brakes.

For convenience of representation the trucks are not shown, and similar letters 25 and figures will designate like parts in the various drawings.

To enable others skilled in the art to make and use my invention I will proceed to describe its construction and operation.

30 I construct my car in any of the known forms, and apply thereto the usual appendages, such as trucks, brake-blocks, cam rods and cams, and also an engineer, brakeman, or conductor's brake-cord communicating 35 with the engine and each and every end of every car (in the manner to be described) so that when this brake-cord or brake-chain is pulled a simultaneous putting down of the brakes may be effected. Toward the 40 center and beneath the bottom of each car I place a swivel bar (b) moving upon a pivot (p). On the opposite sides of the swivel bar, and pressing in opposite directions are springs (S S). To the ends of the swivel 45 (b) bar are fastened chains (c^2 c^2) running to the cam-rods (R). The tongues of the cam-rods and their cams are perpendicular to the bottom of the car when the cars are in motion, either forward or backward, but the 50 cams are pressing against the brake-blocks, and the tongues of the cam rods (t t) are inclined toward the swivel bar and the swivel bar (b) at right angles to the sides of the car (and the springs at rest) when 55 the cars are coming to, or at, a rest or stop. To the cam rods or their tongues, chains

C' C' are also attached, running in the opposite direction to the chains c^2 c^2 . These chains C' C' are fastened to a slide (l), to which slide, at the other end of it, the coupling pin (n) is connected and passes through, allowing the slide and the coupling bar (c—b) to move forward and backward by means of a slot (o—t). When the locomotive is moved forward the coupling bar 60 (c—b) draws the slide forward (and the chains C' C' are of such a length that when drawn toward the ends of the cars, the tongues of the cam rods are perpendicular to the bottom of the car) the cams become 65 free from the brake-blocks, and the brakes up. A cross piece X is attached to the slide (l), and one end (A) of the cross piece is drawn up an inclined plane until it is 70 caught by a shoulder of a trigger as represented at (P), and when thus caught the 75 brakes are up until the engineer or conductor shall choose to put them down. The train now can move forward or backward 80 without hindrance from the brakes.

When the engineer or the conductor or brakeman desires to put down the brakes, he pulls the brake-cord (E, c—d) or chain which runs through each car (after the manner of the common conductor's signal 85 cord to the engineer's bell) and is connected (at each platform, to the under portion of the projection of the roof) to a wheel W (with spiral spring within to bring the wheel, after being revolved, back to its normal condition). This wheel is attached to the engineer's brake-cord (E, c—d), and when the cord is pulled by the engineer 90 brakeman or conductor the wheel revolves upon a pivot until its revolution has brought a lip i—p in contact with and against the bell crank lever (k), pivoted at (K), and pushed the crank (as shown by dotted lines on Drawing No 3) until the crank in its movement has pulled the cord (r—d). This 95 cord (r—d) releases the cross piece X from the shoulder of the trigger at P. The cross piece being released, the slide (l), the chain C' C', and the tongue (t t) of the cam rod (R), are immediately drawn toward the 100 swivel bar (b) by the force of the springs (S S) acting through the chain c^2 c^2 ; and the tongue (t t) of the cam rod being thus drawn toward the ends of the swivel bar (b) the spread of the cams is thrown against 105 the brake blocks, and thus check the motion of the cars. This wheel (W) moves in its 110

revolution, in a direction exactly contrary to the spring within it, and by means of this spring returns to its normal condition so soon as the pull upon the cord, in the hand 5 of the conductor or engineer, ceases. Thus it will be seen that not a second of time elapses from the moment when the engineer or conductor pulls the brake-cord to the period when the brakes are simultaneously applied throughout the entire train, and in 10 the second place it will be observed that it requires no greater power to put down the brakes, simultaneously through the entire train, than is now requisite to pull the common signal cord to the engineer's bell.

I do not claim as new or novel the releasing of brakes by the forward or tractive movement of the train, but

20 1. The mode described of simultaneously

applying, or putting down, brakes by means of the brake-cord (E—c—d), the box spring (W) the crank lever (k), the trigger (P), the cross piece (X), the slide (l) and the swivel bar (b) with its springs S S and 25 S S, arranged as described.

2. I also claim the mode described of instantaneously freeing, relieving, or raising the brakes, and of keeping them free when raised, (until the engineer, conductor or 30 brakesman shall desire to apply them,) by means of the forward or tractive movement of the train in combination with the slide (l) the cross piece (X) and the trigger with its shoulder (P), arranged and operating as 35 described.

ALFRED F. TOULMIR.
